UNITED STATES PATENT OFFICE.

WILLIAM P. STIBBS, OF BELLEVILLE, NEW JERSEY.

PAPER-HOLDER.

SPECIFICATION forming part of Letters Patent No. 510,721, dated December 12, 1893.

Application filed January 26, 1893. Serial No. 459,865. (No model.)

To all whom it may concern:

Be it known that I, WILLIAM P. STIBBS, of Belleville, in the county of Essex and State of New Jersey, have invented a new and useful Improvement in Paper-Holders, of which the following is a full, clear, and exact description.

My invention relates to an improvement in paper holders, and has for its object to provide a device adapted for attachment to a door frame, a door, the side of a house, the walls of a building, or any convenient support, the device being especially adapted to receive and hold newspapers, books, magazines and small parcels.

Another object of the invention is to provide a paper and parcel holder which, when it is opened, will sound an alarm, the alarm being electrically produced, and whereby the alarm will be of short duration and will be stopped after the keeper arm of the device has been opened sufficiently to admit the parcel, the alarm being produced at the first outward movement of the said keeper arm.

It is another feature of the invention to provide a means whereby when electrically operated door bells are employed, the same battery utilized in the circuit of the bell may be used in the circuit in which this device is located.

The invention consists in the novel construction and combination of the several parts, as will be hereinafter fully set forth and pointed out in the claims.

Reference is to be had to the accompanying drawings forming a part of this specification, in which similar figures and letters of reference indicate corresponding parts in all the views.

Figure 1 is a front elevation of the device, illustrating it as applied to a support in which the push button of an electrically-operated door bell is located. Fig. 2 is a section taken vertically through the device and practically on the line 2—2 of Fig. 1. Fig. 3 is a rear elevation of the support to which the device is attached, the support being partially broken away; and Fig. 4 is a detail view of the spring utilized in making and breaking the circuit.

The device proper may be said to consist primarily of a body frame A and a keeper arm B. The body frame is adapted to be at-

tached permanently to a support C of any description by means of screws, nails or their equivalents; and the keeper arm at its lower end has a hinge connection with the body A, the hinge being controlled by a spring 10, which spring acts in a manner to normally keep the upper end of the keeper arm in engagement with the body, or the keeper arm has a tendency to such an engagement. The body and the arm may be of any desired construction, and may be made of any approved material. Usually, however, metal is employed. The keeper arm is generally provided with an attached knob 11, located at its upper end, to facilitate its withdrawal from the body.

Two contact points 12 and 13, are attached at opposite sides of the body, as shown in Fig. 3, the arms extending inward one above the other, and normally they are spaced some distance apart, as illustrated in said Fig. 3. The inner ends of these arms are insulated in any approved manner, and are in connection with binding posts 14, and from each of the binding posts a wire 15 is projected, which wire is in battery connection with an alarm bell, the circuit being run in any manner desired. Preferably, however, the wires 15, are made to connect with the wires 16 in battery connection with the alarm bell 17, utilized and connected with the push button located at the door of the dwelling.

A spring tongue 18, preferably made in the shape of a flat strip is held to slide vertically in suitable bearings located at the back of the body; and the lower end of this tongue is bent inward, as shown in Fig. 2, and is held to slide upon a rod 19, secured to the lower contact point 13, preferably near the inner end of the latter. The rod 19, is encircled by a spring 20, which spring has bearing upon the foot of the spring plate or tongue 18, and likewise upon the under surface of the contact plate 13, so that when the spring plate 18, is forced upward a contact is made between the two plates 12 and 13, and the circuit in which they are located is thereby closed and an alarm will be rung. The spring plate or tongue 18, is elevated through the medium of a trip arm 21, which is attached to the rear face of the keeper arm near the hinged connection of the latter with the body, as shown

in Fig. 2; this arm is beveled at its outer end upon the top, and at said outer end it is of less thickness than at any other point in its length.

5 The tongue or plate 18, is provided with a slot 22, longitudinally produced therein and wider at one portion than at the other, whereby a shoulder 23, is formed. When the keeper arm is close up against the body the trip arm 10 21, passes through the slot 22 in the spring tongue or plate 18, and the upper edge of the trip arm engages with the shoulder 23 of the spring plate.

In operation, the moment that the keeper 15 arm is carried away from the body, the trip arm by engagement with the shoulder 23 of the spring plate 18 elevates that plate and causes an electrical contact to be made between the plates 12 and 13, and an alarm is 20 sounded. When, however, the keeper arm has been opened to such an extent as to admit of a parcel or a paper of ordinary size being placed therein, the trip arm will have been elevated to such a distance that its reduced 25 portion will be presented to the shoulder portion of the spring plate, and the shoulder of the latter will be released and the spring 19, will restore the spring plate to its normal position, which action will carry one of the contact 30 plates out of engagement with the other, breaking the circuit and causing the alarm to cease. It will thus be observed that when the device is first operated an alarm will be sounded which will notify persons within the dwelling that 35 some one is manipulating the device; but after the paper or parcel has been placed therein the alarm is discontinued and the occupants of the dwelling are not annoyed by the constant ringing of the bell.

40 The device is exceedingly useful in preventing papers and small parcels from being blown away, and it also provides a support therefor which will keep such articles from becoming soiled.

45 Having thus described my invention, I

claim as new and desire to secure by Letters Patent—

1. In a paper and parcel holder, the combination with a body and a spring controlled keeper located in front thereof and adapted 50 to clamp papers and the like between it and the said body, of a trip arm carried by the said keeper, a sliding plate adapted to be operated by the same, an electric circuit a part of which is arranged near the body, an alarm device included in the circuit, and means for making and breaking the said circuit by the movement of the said sliding plate, as and for the purpose set forth.

2. In a paper and parcel holder, the combination with a body and a spring controlled keeper pivoted at its lower end to the front side of said body, of a trip arm carried by the said keeper, a vertically sliding plate adapted to be operated by the same, an electric circuit 65 a part of which is arranged near the body, an electric bell included in the circuit, and means for making and breaking the said circuit by the movement of the said sliding plate, as and for the purpose set forth.

3. In a paper and parcel holder, the combination, with a body and contact points projected therefrom one below the other, and a spring controlled keeper arm pivoted to the body, of a plate held to slide upon the body, a rod or 70 bar projected from one of the contact points, a plate having sliding movement upon the rod or bar, a spring bearing against the plate and against the contact point attached to the rod and encircling the rod, and a trip arm carried by the keeper arm and operating to raise and to lower the plate, whereby the contact points are carried into and out of engagement when the keeper arm is opened, as and for the purpose specified.

WILLIAM P. STIBBS.
